RIVET SETTING MACHINE

William Edgar Whitlock, Aylesbury, England, assignor to Judson L. Thomson Manufacturing Company, Waltham, Mass., a corporation of Massachusetts

Application April 22, 1940, Serial No. 330,828
In Great Britain March 9, 1939

4 Claims. (Cl. 218—2)

This invention relates to machines for setting or driving rivets, tacks or the like, herein termed rivet setting machines.

These machines may be provided with automatic rivet feeding mechanism for feeding the rivets to a two-part pocket which receives the rivets and retains them in proper position to be set by the plunger of the machine. Such an arrangement is described in the specification of British Letters Patent No. 487,152, in which the two parts of the pocket are secured rigidly to the lower ends of two blade springs fixed at their upper ends to the stem of the rivet setting machine. This construction and arrangement of the rivet-holding pocket operates quite satisfactorily in normal practice but, with the advent of flush riveting, it has become essential to employ a rivet-setting plunger the diameter of which is at least as large as, and preferably larger than, the diameter of the heads of the rivets being set. This larger diameter plunger opens the two halves of the pocket to a considerable extent and, due to the fact that the two parts of the pocket swing open about the fixed upper parts of the blade springs, they are opened more at the bottom than at the top. This excessive opening of the bottom parts of the pocket may allow the rivet therein to drop to the bottom of the well and turn over, so that when the machine completes its setting stroke, the rivet is squeezed sideways on to the work and may damage the components being riveted. This objection is serious as the type of work in which flush riveting is called for usually comprises expensive light alloy panels for aircraft.

The object of the present invention is to provide an improved construction and arrangement of the two-part pocket with which the aforesaid objection is definitely eliminated.

According to the invention the parts of the pocket are pivotally connected to their supporting members so that when the plunger descends and opens the pocket, the parts open at the top about their pivots while at the bottom they remain close together to prevent the rivet turning sideways or dropping from the pocket.

One embodiment of the invention will now be more particularly described, by way of example, with reference to the accompanying drawing, in which

Figures 1, 2 and 3 illustrate in front elevation, side elevation and plan respectively a rivet receiving and retaining pocket formed in two parts pivotally connected to their supports in accordance with the invention,

Figure 4 is a front elevation of the rivet receiving and retaining pocket of Figures 1 to 3 attached to the rivet-setting machine, a rivet being shown lying in the pocket prior to the descent of the rivet-setting plunger, and

Figure 5 is a similar view to Figure 4 but showing the initial opening of the pocket parts upon descent of the plunger.

Referring to the drawing, the rivet receiving and retaining pockets shown therein is formed by two metal parts 6 machined to form a recess or well 7 for a rivet fed thereto at 8 from an automatic rivet feeding mechanism (not shown) which may be similar to that described in the specification of British Letters Patent No. 15 294,754. The parts 6 are connected each to one of a pair of L-shaped members 9 by hinge pins 10 located at the outer lower ends of the parts, thereby allowing the pocket parts to rock laterally, that is in a vertical plane. The two 20 L-shaped members 9 with the lower horizontal limbs of the L's facing toward each other may be and, as shown, are riveted at 12 to a pair of blade springs 11 which, as shown in Figures 4 and 5, are fixed at their upper ends to the stem 13 of the rivet-setting machine described in the specification of British Letters Patent No. 487,152. This permits a yielding bodily separation of the pocket parts to permit the plunger to pass therebetween and eject a rivet therefrom and set it 30 in the work. This fixing of the blade springs 11 to the stem 13 is effected by studs 14 which are carried by and project outwardly of the stem to pass through apertures 16 in the upper ends of the springs which are secured upon the studs 35 by nuts 15. Pegs 17 are provided to prevent turning of the pocket and spring assembly upon the studs. The stem 13 in the construction illustrated forms part of a pressure pad which sheathes the rivet-setting plunger 18, the apertured bottom plate 13a constituting the pad proper. As will be understood, the rivet-setting machine embodies mechanism to drive the pressure pad downwards slightly in advance of the plunger 18, so that the pad proper 13a maintains a constant pressure on the work during 40 the time that a rivet is being set.

When the plunger 18 descends to pass between the upper parts of the pocket parts 6, 6 its lower edge strikes on the upwardly and outwardly inclined faces of the pocket parts 6, 6, these parts thus having cooperating wedge faces which act to open up the pocket at the top under pressure of the plunger while the pressure of the blade springs 11 exerted on the pivots 10 holds the 45 50 55 60 65

lower ends of the pocket parts 6 together as shown in Figure 5. As the plunger descends further and contacts with the rivet, the pressure of the plunger against the sides of the well 7 approaching lateral alinement with the pivots 10 causes the pocket parts to separate at their lower ends also against the pressure of the springs 11, and the lower end of the plunger passes completely through the pocket driving the rivet before it.

It will be understood that the terms "top" and "bottom" are used herein in a relative sense and that in an underfeed riveting machine, in which the plunger moves upwardly towards an anvil disposed thereabove, the pocket parts will open at the bottom about their pivots and remain close together at the top. That is to say the construction and arrangement of the parts will be as already described except that they will be inverted.

What I claim and desire to secure by Letters Patent is:

1. In a rivet setting machine having a rivet setting plunger, a multiple-part pocket for receiving and retaining a rivet in position to be set by said plunger, supporting members permitting bodily separation of said pocket parts under pressure of said plunger to permit said plunger to pass therebetween and eject a rivet therefrom, and pivotal connections between said supporting members and pocket parts at the lower ends of said pocket parts permitting said pocket parts to tilt from each other as said plunger enters therebetween at their upper ends while remaining close together at their lower ends to retain a rivet in said pocket in position to be properly driven by said plunger, said machine including means for pressing said pivotal connections toward each other.
2. In a rivet setting machine having a rivet setting plunger, a multiple-part pocket for receiving and retaining a rivet in position to be set by said plunger, supporting members permitting bodily separation of said pocket parts under pressure of said plunger to permit said plunger to pass therebetween and eject a rivet therefrom, pivotal connections between said supporting

members and pocket parts at the lower ends of said pocket parts permitting said pocket parts to tilt from each other as said plunger enters therebetween at their upper ends while remaining close together at their lower ends to retain a rivet 5 in said pocket in position to be properly driven by said plunger, said machine including means for pressing said pivotal connections toward each other, and a work engaging pad beneath said pocket. 10

3. In a rivet setting machine having a rivet setting plunger, a multiple-part pocket for receiving and retaining a rivet in position to be set by said plunger, and supporting members permitting bodily separation of said pocket parts under pressure of said plunger to permit said plunger to pass therebetween and eject a rivet therefrom, each of said supporting members being L shaped and with the lower limbs thereof 20 facing inwardly toward each other, each of said pocket parts being hinged at its outer lower end to one of said lower limbs of its respective supporting member, and said pocket parts having faces extending above said hinges sufficiently close 25 together to be engaged and forced apart by said plunger during its setting stroke, said machine including means for pressing said pocket parts toward each other.

4. In a rivet setting machine having a rivet setting plunger, a multiple-part pocket for receiving and retaining a rivet in position to be set by said plunger, resilient supporting members permitting yielding bodily separation of said pocket parts under pressure of said plunger to 30 permit said plunger to pass therebetween and eject a rivet therefrom, pivotal connections between said supporting members and pocket parts permitting said pocket parts to be tilted from each other by the pressure of said plunger thereagainst as said plunger enters therebetween at 35 their upper ends while remaining close together at their lower ends to retain a rivet in said pocket in position to be properly driven by said plunger, and a pressure pad supported beneath said pocket parts. 40 45
